JOURNAL BOX COVER

Ernest R. Viberg, Montreal, Quebec, Canada

Application October 30, 1933, Serial No. 695,875

9 Claims. (Cl. 308—47)

This invention relates to covers for journal boxes and particularly to covers of the hooded type in which the lid portion is carried by a hood that fits over and is pivotally secured to the journal box lug and serves as a housing for a torsion spring which reacts against the central portion of the lid and the cam faces of the lug to hold the cover in closed or open position.

The principal object of the present invention is the provision of an improved cover assembly of this type which may be very easily applied to the journal box or removed therefrom.

Another object is the provision of a novel form of shoe through which the pressure of the torsion spring is exerted against the journal box lug in a more efficient manner for holding the lid tightly against the mouth of the journal box opening when the lid is in its closed position.

A still further object is to design the aforementioned shoe so that a retaining pin may be conveniently passed through complementary openings in the shoe and in the wall of the hood to hold the torsion spring and shoe in a retracted position to facilitate the application and removal of the cover assembly.

Proceeding now to a more detailed description of the invention, reference will be had to the accompanying drawings, wherein Fig. 1 is a front view of a cover assembly provided in accordance with this invention.

Fig. 2 is a vertical sectional view along the line 2—2 of Fig. 1. In this view the cover assembly is shown applied to the journal box.

Fig. 3 is a view similar to Fig. 2 but showing the lid portion of the cover slightly removed from the mouth opening of the journal box.

Fig. 4 is a view similar to Figs. 2 and 3 but showing the cover assembly in its fully opened position.

Fig. 5 is a view in vertical section of the shoe through which the pressure of the torsion spring is applied to the journal box lug.

Fig. 6 is a view showing the shoe in side elevation.

Fig. 7 is a top plan of the shoe.

Fig. 8 is a view of the shoe in front elevation.

Fig. 9 is a front view, partly broken away, of a modified cover assembly provided in accordance with this invention.

Fig. 10 is a vertical sectional view along the line 10—10 of Fig. 9.

Fig. 11 is a top plan view of a shoe forming part of the assembly appearing in Figs. 9 and 10.

Fig. 12 is a front elevation of the shoe shown in Fig. 11.

Fig. 13 is a side elevation of said last mentioned shoe.

As shown in these drawings, my improved cover assembly comprises a lid 11, a hood 12, a torsion spring 13 and a shoe 14. The lid 11 is in the form of an imperforate plate adapted, in the closed position of the cover assembly, to fit snugly against the front face of the journal box 15 so as to completely close the journal box opening 16. The hood 12 comprises a top wall 17, side walls 18 and a front wall 19. The upper portions of the side walls 18 are provided with integral pintle receiving sleeves 20 and 20a which are aligned in the journal box lug 21 to receive the hinge pintle 22. In the present instance the pintle receiving sleeve 20 is provided with a stop flange 23 for engagement with one end of the pintle while the companion sleeve 20a is fitted with a tubular pintle retainer 24 having pintle retaining tongues 25 adapted to be bent inwardly over the opposite end of the pintle. This method of securing the pintle in place is more fully described in my co-pending application Serial No. 653,870, filed Jan. 27, 1933.

The side walls 18 of the hood project below the front wall 19 to approximately the middle portion of the lid 11 and are provided at their lower extremities with openings 26 registering with similar openings 27 formed in lugs 28 cast integral with the outer face of the lid. The spring 13 comprises two coils 29 and 30 connected by an intermediate U-shaped extension 31 which constitutes an integral continuation of the inner terminal convolutions of the coils and carries the shoe 14. The outer convolutions of the coils 29 and 30 are extended to provide a pair of side arms 32 having their lower ends bent outwardly to provide pin-like portions 32a which extend outwardly through the openings 27 of the lugs 28 and through the registering openings 26 of the hood, thus affording a pivotal connection between the central portion of the lid and the side walls of the hood. This type of pivotal connection between the hood and lid is more fully described and claimed in my co-pending application No. 653,870, filed Jan. 27, 1933. In this prior application I have also shown and described various connections between the upper portions of the hood and lid for limiting their relative movement and it will be understood that any of such connections may be employed in conjunction with the cover assembly of the present invention. In the present drawings one such connection is generally indicated at 11a (Fig. 1) but need not be described in 55

detail since it forms no essential part of the present invention.

The front wall 19 of the hood has its lower portion curved to provide a fulcrum pocket 34 (Fig. 2) in which the spring coils 29 and 39 are seated so that the spring pressure is applied to the central portion of the lid through the side arms 32 and to the journal box lug 21 through the U-shaped extension 31 and the shoe 14. The shoe 14 is provided with a horizontal bore 35 by means of which it is rockably mounted on the bight portion of the U-shaped spring extension 31. In order to limit the rocking movement of the shoe with respect to the extension 31 the side members of the latter are fitted in grooves 36 provided in opposite sides of the shoe. These grooves constitute curved continuations of the bore 35 and are made slightly flaring towards their lower ends and of a width sufficient to permit the shoe to have a slight independent pivotal or rocking movement. At the inner side of the bore 35 the shoe is provided with a flat face 37 adapted to ride the flat angularly related cam faces 21a and 21b of the journal box lug 21. The flat face 37 ensures a substantial area of contact between the shoe and the lug while the pivotal mounting of the shoe enables it to adjust itself to ensure proper engagement between the lug and the flat face 37, irrespective of variations in the dimensions of the lug, or in the inclination of the cam faces against which the flat face of the shoe is adapted to bear. At the opposite or outer side of the bore 35 the shoe is provided with a vertical opening 38 adapted at times to register with a similar but slightly larger opening 39 formed in the top wall 17 of the hood.

When the cover assembly of this invention is to be applied to the journal box the U-shaped extension 31 of the torsion spring 13 is forced towards the front wall of the hood until the opening 38 of the shoe is in line with the opening 39 of the hood. A retaining pin 40 is then passed through these openings to hold the shoe in its retracted position. The cover assembly is then arranged as shown in Fig. 4 with the pintle receiving sleeves 20 and 20a disposed at opposite sides of the journal box lug 21 to receive the pintle 22 which is then pushed into place and secured by bending down the tongues 25 of the tubular retainer 24. The cover assembly is then swung from the position shown in Fig. 4 to the position shown in Fig. 3. In this latter position the shoe 14 is engaged by the high point 21c of the journal box lug 21 and is forced towards the front wall of the hood a sufficient distance to relieve the lateral pressure on the retaining pin 40 so that the latter can be easily withdrawn from the openings 38 and 39. The cover assembly is then swung to the completely closed position shown in Fig. 2. In subsequent manipulation of the lid to its open or closed positions the pivotal mounting of the shoe on the spring extension 31 and the flat lug engaging surface 37 of the shoe enables the torsion spring to act more effectively both with respect to holding the lid in its open or closed positions and with respect to ensuring tight closure of the lid against the mouth portion of the journal box. The pivotal mounting of the shoe also ensures proper alignment of the shoe opening 38 with the opening 39 of the hood when the shoe is forced back to provide for the application or removal of the retaining pin 40. When the cover assembly is to be removed it is first swung from the closed position shown in Fig. 2 to the partially open position shown

in Fig. 3. In this last position the shoe is forced back by the highpoint 21c of the lug 21 so that its pin receiving opening 38 registers with the pin receiving opening 39 of the hood. The retaining pin 40 is then passed through these openings to hold the shoe in its retracted position during further movement of the lid assembly to the position shown in Fig. 4. In this last position it will be noted that the shoe is entirely removed from the lug so that the pressure of the torsion spring 10 will not interfere with the withdrawal of the hinge pintle 22 following the straightening out of the pintel retaining tongues 25.

In the modified construction shown in Figs. 9 to 13 inclusive, the previously mentioned shoe 14 is replaced by a different type of shoe generally indicated at 14a. This shoe 14a includes a curved shank 14b having lateral extensions 14c at its lower end forming bearing trunnions which are fitted in the coils 29 and 30 of the spring 13 so that the shoe is thus mounted to have a slight independent pivotal movement with respect to said spring. At its upper end the shank 14b is provided with a forwardly projecting horizontal flange 14d having a vertical opening 14e registering with a similar opening 14f formed in the shank. At the juncture of the shank 14b and the flange 14d the shoe is shaped to provide a flat face 14h adapted to ride the flat angularly related cam faces 21a and 21b of the journal box lug 21. The projection 14d forms with the curved outer surface of the shank 14b a recess 14j in which the bight portion of the U-shape spring extension 31 is fitted, as shown to advantage in Fig. 10.

When the cover assembly shown in Fig. 10 is swung from the position shown in this figure to an open position corresponding to that shown in Fig. 3, the shoe 14a will be forced towards the front wall of the hood until the openings 14e and 14f of the shoe are aligned with the opening 39 of the hood. The previously mentioned retaining pin 40 is then passed through these openings to hold the shoe in its retracted position. The opening movement of the cover assembly may then be continued until it reaches a position such as that shown in Fig. 11 where the shoe is entirely removed from the lug so that the pressure of the torsion spring will not interfere with the withdrawal of the hinge pintle 22. The method of applying the cover assembly shown in Figs. 9 and 10 is substantially the same as that previously described in connection with Figs. 1 to 4 inclusive.

Having thus fully described what I now consider to be the preferred embodiment of my invention it will be understood that various minor changes may be resorted to in the construction and arrangement of the parts within the scope and spirit of the appended claims.

Having thus described my invention, what I claim is:—

1. A journal box cover assembly comprising a lid, a hood, a spring confined between the lid and hood, and a shoe carried by the spring for engagement with the lug of a journal box, said shoe and hood being provided with complementary openings adapted to be aligned to receive a removable retaining pin for temporarily holding the shoe in a retracted position against the pressure of the spring to facilitate application or removal of the lid.

2. A journal box cover assembly comprising a lid equipped with a hood adapted to fit over the lug of a journal box, a spring comprising spaced coils located at the upper edge of the lid and

bearing against the inner surface of the hood and connected to each other by an upwardly projecting extension of inverted U-shape constituting an integral continuation of the inner terminal convolutions of the coils and projecting beyond the said upper edge of the lid, the outer terminal convolutions of the coils being extended downwardly into engagement with the central portion of the lid, and a journal box lug engaging shoe mounted on the bight portion of said extension so as to be capable of a limited independent pivotal movement, said shoe being formed with a flat lug engaging face.

3. A journal box cover assembly as claimed in claim 2 in which the the shoe and hood are provided with openings adapted to register with each other when the shoe is retracted to a predetermined position against the resistance of the spring.

4. A journal box cover assembly comprising a lid equipped with a spring of approximately inverted U-shape, and a journal box lug engaging shoe provided with a flat lug engaging face and with a horizontal bore through which the bight portion of the spring extends, the side arms of the spring being fitted in flaring grooves formed in the opposite side of the shoe, said grooves being of sufficient width to permit a limited pivotal movement of the shoe on the bight portion of the spring.

5. A journal box cover assembly as claimed in claim 4 including a hood affording a housing for the spring and shoe and adapted to partially enclose the journal box lug, said hood and shoe being provided with openings adapted to register with each other when the shoe is retracted to a predetermined position against the resistance of the spring.

6. A journal box lid assembly comprising attached lid and hood members, said hood member having a top wall provided with a vertical opening, a spring comprising laterally spaced coils bearing against the inner surface of the hood member and having their outer terminal convolutions extended to bear against the central portion of the lid member, the inner terminals of said coils being connected by an upwardly projecting integral extension of inverted U-shape, a journal box lid engaging shoe comprising a shank embraced by said extension and presenting lateral projections at its lower end fitted in said coils and a projection at the upper end of the shank overhanging the spring extension and provided

with a vertical opening adapted, at times, to register with the opening in the top wall of the hood.

7. A journal box lid assembly as claimed in claim 6 in which the shank of the shoe is also provided with a vertical opening in line with the opening formed in said projection. 5

8. A journal box cover assembly comprising a lid, a hood overlying and projecting beyond the upper edge of the lid, a spring comprising spaced 10 coils located adjacent the upper edge of the lid and bearing against the inner opposing surface of the hood, said coils being connected to each other by a U-shaped extension projecting beyond the upper edge of the lid and constituting an integral 15 continuation of the inner terminal convolutions of the coils, the outer terminal convolutions of the said coils being extended downwardly to bear against the central portion of the lid, and a journal box lug engaging shoe presenting an upper 20 portion against which the bight of the U-shaped extension bears and a lower portion provided with lateral trunnions loosely fitted in said coils, said upper portion of the shoe being provided with an opening adapted to be aligned with an opening 25 in the hood to receive a retaining pin for holding the shoe in a retracted position against the pressure of the spring.

9. A journal box cover assembly comprising a lid, a hood overlying and projecting beyond the 30 upper edge of the lid, a spring comprising spaced coils located adjacent the upper edge of the lid and bearing against the inner opposing surface of the hood, said coils being connected to each other by a U-shaped extension projecting be- 35 yond the upper edge of the lid and constituting an integral continuation of the inner terminal convolutions of the coils, the outer terminal convolutions of the said coils being extended downwardly to bear against the central portion of the 40 lid, and a journal box lug engaging shoe presenting an upper portion against which the bight of the U-shaped extension bears and a lower portion provided with lateral trunnions loosely 45 fitted in said coils, said upper portion of the shoe terminating in a projection overlying the spring extension and provided with an opening adapted to be aligned with an opening in the top wall of the hood to receive a retaining pin for holding 50 the shoe in a retracted position against the pressure of the spring.

ERNEST R. VIBERG.
